ADJUSTABLE VISCOSITY SENSITIVE
BURNER CONTROLRaymond B. Plass, Berkeley, Calif., assignor, by
mesne assignments, to Ray Oil Burner Co., a
corporation of California

Application August 30, 1949, Serial No. 113,172

3 Claims. (Cl. 137—166)

1

This invention relates to burner controls for oil burners or the like which are sensitive to viscosity in the manner generally described in my Patent No. 2,471,541 of May 31, 1949, entitled "Burner Control System Including a Viscosity Sensitive By-Pass Valve."

The use of viscosity controls in an oil burner system is now known and an example of such use is given in the above mentioned patent. The viscosity sensitive valve is employed in a system where a constant volume pump directs oil toward an oil burner and the rate of burning or volume of oil delivered to the burner is controlled by by-passing a given quantity of the constant volume pump output back to the source of supply. In order to avoid variation in flame rate at the burner because of variations in viscosity of the oil as it is being delivered, viscosity controls in the form of Poiseuille tubes are interposed in the burner supply line and in the by-pass line to maintain a constant ratio of flow through these two lines regardless of variations in the viscosity. Two undesirable conditions are encountered in this type of control as previously made, one being that the Poiseuille tubes or viscosity control units have been so arranged that their simple or automatic adjustment to vary flame rate at the burner has been impractical so that an additional by-pass valve in the return line has been provided for this purpose. The other disadvantage is that back pressure in the line leading it to the burner and in the by-pass line effects the viscosity control units and any variation in back pressure that would result from adjustment of the units would tend undesirably to vary the intended ratio of flow.

The present invention is concerned with the correction of the disadvantages mentioned above and has for its object the provision of a viscosity sensitive burner control that is adjustable to vary flame rate at the burner entirely through simple mechanism that alters the positions of the viscosity control members and automatically corrects for any variation in back pressure affecting said members. Further and more specific objects and advantages of the invention and the mechanism through which it is carried into practice are disclosed in the following specification by reference to the accompanying drawings.

In the drawings:

Fig. 1 is a schematic view of a burner control system embodying the present invention, and

Fig. 2 is an enlarged central longitudinal section through the viscosity control units shown

2

in Fig. 1 illustrating the manner of their support and adjustment.

The burner control system, illustrated schematically in Fig. 1, comprises a burner tip 10 which is disposed in the fire box of a furnace or the like, not shown, and to which oil and air are delivered in a conventional manner to produce a combustible mixture. The rate of flow of oil to the burner tip 10 determines the size 10 of the flame in the fire box and the present invention is concerned with controlling and adjusting this rate, it being desirable to maintain a constant rate of burning for any given setting. The oil consumed at the burner is supplied 15 from a source not shown through a pipe 11 being withdrawn therefrom and delivered by a pump 12 to the interior of a reservoir 13. An overflow tube 14 communicates between the reservoir and the source of supply to prevent the building up 20 of excessive pressure in the reservoir. A pump 15, disposed like the pump 12 within the reservoir, is employed for supplying oil to the burner tip 10. A so-called viscosity valve, generally indicated at 16, receives oil from the pump 15 25 through a pipe line 17 and functions to direct a part of the output of the pump 15 to the burner 10 and to by-pass the remainder back to the reservoir 13 and thence, if necessary, through the return line 14 to the source of supply. The capacity of the pump 15 is in excess of the maximum requirements of the burner 10 so a portion 30 of the oil flows toward the burner through a tapered port 19 in the viscosity valve controlled by an adjustable tapered plug 20. The remainder of the oil flows through a similar but oppositely directed tapered port 21 with a corresponding adjustable tapered plug 22. These tapered passageways are controlled by their respective plugs and form Poiseuille tubes and thus 35 Poiseuille's law becomes effective to maintain a constant ratio between the rate of flow to the burner and rate of flow through the return line regardless of variations in viscosity of the oil. While the theory of viscosity control, herein discussed, has been employed in oil burner systems, the present invention provides a new arrangement of the control units which simplifies their adjustment for maximum firing rate as well as their adjustment for automatic or manual flame 40 control during operation.

As shown in the drawing, the tapered passageways 19 and 21 are axially aligned in end to end relationship as are also the tapered plugs 20 and 22. The plugs 20 and 22 are carried on a common 55 supporting assembly generally indicated at 24

presently to be more specifically described and including a toothed or racked portion 25 adjacent one of its ends. This bar is adjustable axially or lengthwise of the valve housing through means herein illustrated as a gear 26 meshing with the rack 25. The gear 26 is carried on a rotatable shaft 27 and a lever 28, connected to the shaft and disposed exteriorly of the housing, may be manipulated to move the supporting assembly and plugs 20 and 22 lengthwise with respect to the housing. The gear and rack assembly is of course only typical of many mechanical devices capable of imparting the desired movement to the tapered members of the viscosity valve. As shown in Fig. 1, the delivery pipe 17 is connected with the central portion of the viscosity valve and oil flows outwardly toward opposite ends of the valve for distribution to the burner tip and the return line. That part of the oil to be directed to the burner tip passes through a conduit 29 through a pressure balancing valve, generally indicated at 30, and then through line 31 to the burner tip. The oil to be returned to the source of supply leaves the viscosity valve by means of a conduit 32, the pressure balancing valve 30 and a return line 33 interposed between the balancing valve and the reservoir 13. A suitable shut-off valve, usually of the magnetic type, is disposed in the line 31 which leads to the burner tip as indicated at 34.

The lever 28 may be manipulated to control the rate of firing as upon movement to the right, it will move the plugs 20 and 22 to the right with respect to the tapered openings 19 and 21 in which they are disposed, thus reducing the cross-section of the flow area in the opening 19 and at the same time, increasing the cross-section of the flow area in the opening 21. The reverse effect is obtained by movement of the lever 28 toward the left and this lever is intended either for manual operation or for connection with any suitable automatic control mechanism not shown. One of the advantages of the present invention results from the arrangement of the tapered plugs 20 and 22 in the manner shown to permit of their simultaneous adjustment by simple movement of a single lever. Also the force required for adjustment is minimized by the balance of the hydraulic thrusts in this assembly.

It is also desirable that the members 20 and 22 be adjustable relative to each other in order to establish a maximum desired firing rate for the burner and this is accomplished through the supporting assembly 24 which is illustrated in detail in Fig. 2. The assembly 24 comprises a slidable and rotatable rod 36, shown in Fig. 1, as extending through a packing joint 37 at one end of the housing 16 so that its end projects to a position where it is accessible for rotation by a screw driver or other suitable tool. Pinned to the rod for rotation therewith is a sleeve 38 with a longitudinal slot 39 formed therein. The tapered member 22 embraces one end of this sleeve and has a pin 40 extending into the slot 39 to permit it to slide relative to the rod but to compel it to rotate with the rod. A second sleeve 41 is slidably mounted on the rod 36 and pinned to the tapered member 22 as by a pin 42. This sleeve 41 has a threaded connection with an axial bore of the tapered member 22 so that upon rotation of the rod 36, the members 20 and 22 will be adjusted to and away from each other as desired. Such adjustment of course effects the maximum possible flow through the passage 19 when the lever 28 is swung to its extreme left

position. The rack part 25 is also shown as slideable on the rod 36 and is connected as by a threaded joint with the tapered member 22. This threaded connection may be soldered or otherwise permanently secured after it is made up to prevent a relative rotation of the tapered member 22 and the rack part 25. It is preferred that the rack 25 and the gear 26 be relatively wide across their respective toothed surfaces and this construction prevents rotation of the rack part when it is assembled and in mesh with the gear. The end 44 of the rod 36 may be received in a suitable bore in the interior of the housing, as shown in Fig. 1.

15 The pressure balancing valve 30 comprises a cylindrical housing, as shown, with the oil delivery line 29 and the oil return line 32 connected with its opposite ends. The housing contains a balanced floating piston assembly including two 20 pistons 46 and 47 slidably mounted in the housing and also slidable on an axially arranged bar 48. A spring 49 is interposed between the pistons 46 and 47 and tends normally to urge them outwardly or away from each other. A central stop collar 50 and end collars 51 are fixed to the bar 48 and limit the travel of the pistons thereon.

In operation, oil pressure in the lines 29 and 32 which communicate with the discharge ends of the two viscosity units urges the pistons 46 and 47 toward each other against the pressure of the spring 49 to open communication with the pipe 31 leading to the burner and with the pipe 33 communicating with the reservoir 13 and the system functions as heretofore described. If, upon adjustment of the viscosity controls or for any other cause, the pressure in either of the lines 29 or 32 exceeds the pressure in the other line, the entire piston assembly in the valve 30 will be urged away from the high pressure end of the cylinder and toward a position where the piston on the opposite end closes the discharge port communicating with the line 31 or 33. With this port closed or partially closed, the pressure will build up until it equalizes that from the opposite side and the piston assembly will, through this valving action, come to rest at a point where the fluid pressure in its opposite ends is equal. A drain line 53 preferably communicates between the central portion of the valve 30, between the pistons 46 and 47 and the reservoir 13 so that any oil that might leak past the pistons is free to return to a low pressure area. Because the valve 30 maintains equal operating pressure at the discharge ends of the Poiseuille tubes, the volumetric ratio of delivery through the tubes will remain constant for any setting.

I claim:

1. A viscosity control system for burners or the like which comprises a housing having a pair of axially aligned oppositely disposed tapered fluid passages, a tapered control plug in each passage, a supporting assembly for said plugs including a member extending axially through both passages, rotatable means on said member with a threaded connection with one plug to vary the relative positions of the plugs, and slidable means on said assembly to adjust both plugs with relation to the passages.

2. A viscosity control system for burners or the like which comprises a housing having a pair of axially aligned oppositely disposed tapered fluid passages, a tapered control plug in each passage, a supporting assembly for said plugs including a member extending axially through both passages, rotatable means on said member with a threaded

connection with one plug to vary the relative positions of the plugs, slidable means on said assembly to adjust both plugs with relation to the passages and means operable from the exterior of the housing to actuate said slidable means.

3. A viscosity control system comprising a pair of controlled passages for reception of fluid from a single source, a discharge area for each passage, a pressure balancing valve communicating with the discharge of both passages to maintain equal pressures adjacent the discharge areas of the passages, said valve comprising a cylinder communicating at each end with one of said passages and having side wall outlets, a pair of pistons slidable in the cylinder to valve said outlets, and resilient means urging the pistons apart and opposed by pressure in the cylinder ends to urge them together and open said outlets, said pistons

and resilient means being slidable as a unit in the cylinder whereby high pressure at one end of the cylinder tends to close the outlet for the other end.
